UNITED STATES PATENT OFFICE.

HENRY MAHNKEN AND CLARENCE L. HEALY, OF BROOKLYN, ASSIGNORS TO
THE COMMERCIAL TELEGRAM COMPANY, OF NEW YORK, N. Y.

PRINTING-TELEGRAPH RECEIVER.

SPECIFICATION forming part of Letters Patent No. 366,178, dated July 5, 1887.

Application filed February 1, 1887. Serial No. 226,144. (No model.)

To all whom it may concern:

Be it known that we, HENRY MAHNKEN and CLARENCE L. HEALY, of Brooklyn, in the county of Kings and State of New York, have 5 jointly invented a certain new and useful Improvement in Printing-Telegraph Receivers, of which the following is a specification.

The object we have in view is principally an improved escapement or type-wheel movement 10 for printing-telegraph receivers which will be capable of a high rate of vibration and will work with certainty and with abundant power.

A further object is an arrangement of the inking-rollers which ride on the type-wheels 15 so that the type-wheels will be more uniform and steady in their movement, they will be inked more uniformly, and the operation of the machine made more certain.

In the accompanying drawings, forming a 20 part hereof, Figure 1 is an elevation of the upper part of the machine from the type-wheel side; Fig. 2, a front elevation of the same; and Fig. 3, a horizontal section on the line 3 3 in Fig. 2, with the electro-magnet coils in elevation.

A and A' are the side plates of the machine, which support the mechanism. They carry 25 two weight-trains, as will be readily understood, terminating in wheels a a', which engage with pinions b b' on the shafts carrying the type-wheels B B'. The type-wheel shafts are arranged one as a sleeve over the other, the type-wheels being located outside of the side plate A', and between it and a bracket, 30 c, secured thereto. A unison rock-shaft, C, carries arms d d', which engage alternately with pins e e', alternately locking the type-wheel shafts at unison, one shaft being always free to be turned by its driving-train.

40 The type-wheel shafts have escape-wheels D D', arranged side by side centrally between the side plates, A A', and with these escape-wheels engage a laterally-vibrating escapement-anchor E. The anchor E is carried by a 45 vertical spindle, f, which is pivoted between a block, f', and a screw, f'', the spindle having a collar which rests on the block f'. Upon this spindle f, above the block f', is mounted an armature, F, which is a short tube of soft

iron, transversely through the center of which 50 the spindle f passes.

G is a permanent magnet which turns back upon itself, as shown, and has its poles N S in the same horizontal plane. This magnet is 55 large and powerful. It is preferably made of cast-iron, and after being drilled and fitted is hardened by chemicals, and it is then magnetized. The pole N of the permanent magnet is grooved or hollowed out laterally, as shown at 60 g, and in this recess the tubular armature F vibrates. The pole of the permanent magnet partly incloses the tubular armature and forms a strong inductive field in which it plays. The recess g is brought close to the armature F at the pivot of the armature, but slopes backward 65 from this point to the ends of the recess, so as to approach as closely as possible to the armature without interfering with its movement.

H is an electro-magnet which is mounted 70 upon the pole S of the magnet G, with its cores in the same horizontal plane as that occupied by the armature, toward which they project. Two screws, h h', pass loosely through holes in the pole S, without engagement of screw-threads therein, and enter the yoke of the electro-magnet, in which they engage with screw-threads. A central screw, i, turns through a screw-threaded hole in the pole S, and sets 75 against the back yoke of the electro-magnet between the screws h and h'. By means of 80 these three screws the approach of the cores of the electro-magnet to the tubular armature may be varied and adjusted, and the angular position of the electro-magnet cores with relation to such armature can also be adjusted. 85 The cores of the electro-magnet H are provided on their ends with extension polar plates k k', which project toward each other. The tubular armature F is flattened on its side next to the electro-magnet, so as to approach the pole- 90 plates k k' with the maximum exposure of surface, and this flat face of the armature is provided with a brass plate, l, which prevents the armature from sticking to the pole-plates k k' which it strikes in its movement, the armature 95 being limited in its movement by the pole-plates.

The tubular armature gives a large induc-

tive surface with the minimum weight, and the poles of the electro-magnet are removed a greater distance from the permanent magnet, at the same time that the relation of the armature is intimate with both of these elements.

By providing the electro-magnet with inwardly-projecting polar extensions a short armature can be used with a large and powerful electro-magnet. This polarized escapement is capable of an exceedingly high rate of vibration and is powerful and certain in its action. Its office, as will be well understood, is to vibrate the escapement-anchor E and permit the type-wheel shaft which is not locked at unison to be revolved by its driving-train.

With reference to the remaining feature of our invention the inking-rollers are shown at I I'. These are carried by pivoted arms m m', and ride upon the type-wheels. Our improvement in this respect consists in providing the inking-rollers with a spring-tension acting to hold them constantly upon the type-wheels. To accomplish this in a simple manner, we connect the arms m m' by a light spring, n, which tends to draw the rollers together and upon the type-wheels.

This device, while simple in its character, is far reaching in its effects. Without the spring-tension the inking-rollers are caused to jump on the type-wheels by the projecting types, and the result is that the machine is made unsteady in its movements, even to the extent of occasionally throwing the wheels out of unison, and, in addition, the inking is not performed uniformly. The spring-tension cures these defects.

What we claim is—

1. In a printing-telegraph receiver, the combination, with the escapement-anchor, of a permanent magnet, an electro-magnet, and a tubular or hollow armature polarized by such permanent magnet, substantially as set forth.
2. In a printing-telegraph receiver, the combination, with the escapement-anchor, of a permanent magnet having a recessed pole, an electro-magnet, and an armature vibrating in

the recess of the permanent magnet and partly inclosed thereby, substantially as set forth.

3. In a printing-telegraph receiver, the combination, with the escapement-anchor, of a permanent magnet having a recessed pole, an electro-magnet, and a tubular or hollow armature vibrating in the recess of the permanent magnet and partly inclosed thereby, substantially as set forth.

4. In a printing-telegraph receiver, the combination, with the escapement-anchor, of a permanent magnet, a vibrating armature, an electro-magnet, and means for adjusting the electro-magnet to vary its distance from the vibrating armature and its angular relation thereto, substantially as set forth.

5. In a printing-telegraph receiver, the combination, with the escapement-anchor, of a permanent magnet, a vibrating armature, an electro-magnet, and means for adjusting the electro-magnet to vary its distance from the vibrating armature and its angular relation thereto, said vibrating armature being limited in its movement by striking the poles of such electro-magnet, substantially as set forth.

6. In a printing-telegraph receiver, the combination, with the escapement-anchor, of a permanent magnet, an electro-magnet having extension pole-plates projecting inwardly, and a short hollow or tubular vibrating armature, substantially as set forth.

7. In a printing-telegraph receiver, the combination, with the escapement-anchor, of a permanent magnet, an electro-magnet, and a tubular vibrating armature located between the poles of the electro-magnet and one pole of the permanent magnet, having its side next to the electro-magnet flattened, substantially as set forth.

This specification signed and witnessed this 25th day of January, 1887.

HENRY MAHNKEN.
CLARENCE L. HEALY.
